(57) **CLAIM**

The ornamental design for a baseball bat as shown and described.

DESCRIPTION

FIG. 1 is a perspective top front right view of a baseball bat, showing my new design;

FIG. 2 is a perspective bottom rear left view thereof;

FIG. 3 is a front elevation view, wherein the rear elevation view, right elevation view, and left elevation view are identical images thereof;

FIG. 4 is a top plan view thereof; and,

FIG. 5 is a bottom plan view thereof.

The broken lines show portions of the baseball bat and form no part of the claimed design.
